(57) **CLAIM**

The ornamental design for a light therapy device stand, as shown and described.

DESCRIPTION

FIG. 1 is a top perspective view of my design for a light therapy device stand;

FIG. 2 is a bottom perspective view thereof;

FIG. 3 is a front elevation view thereof;

FIG. 4 is a back elevation view thereof;

FIG. 5 is a right view thereof;

FIG. 6 is a top plan view thereof;

FIG. 7 is a bottom plan view thereof; and,

FIG. 8 is a front perspective view thereof.

The left side is a mirror image of the right side.

The broken lines in the form of a red light therapy device in FIG. 8 depict environmental subject matter and form no part of the claim thereof. All the other broken lines shown in the drawings depict portions of the light therapy device stand that form no part of the claimed design.
